UNITED STATES PATENT OFFICE

2,313,163

FRONT MARGIN STOP MEANS FOR DUPLICATING MACHINES

Morris P. Neal, Quincy, Ill., assignor to Ditto, Incorporated, Chicago, Ill., a corporation of West Virginia

Original application April 7, 1939, Serial No. 266,518. Divided and this application October 25, 1941, Serial No. 416,540

9 Claims. (Cl. 101—132)

My invention relates to duplicating apparatus and particularly to an improved form of black-print duplicating apparatus employing a master sheet in the form of a thin sheet of aluminum or the like upon which a suitable ink repellent may be spread for controlling the effective application of ink to the sheet. My present improvements are not, however, to be restricted to use in connection with this type of machine, so far as they are applicable to other types of machines.

My invention has for its object the provision of an improved form of stop mechanism for the copy sheets adapted to cooperate effectively with the sheet feeding means for insuring that the successive sheets shall be presented in accurately aligned position. For attaining this result, I have provided an opening in the wall of the drum at one side portion with stop mechanism movably mounted in said opening so as normally to be carried around by the drum together with means adapted to engage the stop mechanism upon each succeeding revolution of the drum for holding the stop mechanism stationary for a short period upon each revolution of the drum, such holding means being arranged so as to release the stop mechanism for the sheets in timed relation with respect to the rotation of the drum for permitting the sheets to go forward by the action of the drum and the cooperating platen or impression roller in the desired adjusted position with respect to the master sheet carried by the drum.

In my improved construction, a margin stop bar is mounted between two arms which are adapted to swing about the axis of the drum, spring means being provided for holding the arms swung forward to the limit of their motion on the drum. Latch means adjacent to the drum engages the stop bar mechanism at a predetermined point in each revolution of the drum, serving to hold the stop bar stationary for a moment while the drum continues to revolve until the drum in its changed position with respect to the stop bar forces the stop bar mechanism out of engagement with the latching means so as to permit the spring means to return the stop bar again to its normal rest position on the drum.

It is another object of my invention to improve mechanisms of this type in sundry details herein-after pointed out. The preferred means by which I have accomplished my several objects are illustrated in the accompanying drawings, in which—

Fig. 1 is a vertical sectional view through my

improved machine adjacent to one end of the drum;

Figs. 2 and 3 are views similar to Fig. 1 but showing changed positions of the parts; and

Fig. 4 is a vertical sectional view on an enlarged scale through a portion of the improved sheet stopping means carried by the drum, with the parts in substantially the same relative position as is shown in Fig. 1.

10 Referring now to the several figures of the drawings, in which corresponding parts are indicated by the same reference characters, 10 indicates a framework supporting a heavy shaft 11 having a drum fixedly mounted thereon, such 15 drum comprising sections 12 and 13, the section 12 being of slightly greater diametrical size than that of the section 13. The drum section 13 is provided with an ink pad 14 wrapped thereabout for receiving a supply of ink from any suitable 20 source. The drum section 12 is provided with a master sheet 15 formed of aluminum or other suitable material and secured firmly upon the drum section by any approved holding means. As is clearly shown in Fig. 1, the drum sections 25 12 and 13 are spaced apart circumferentially so as to provide a substantial opening at 16 in the peripheral wall of the drum as a whole.

Below the drum, an impression roller 17 is rotatably mounted in position for engagement 30 with the face of the master sheet 15 as the drum rotates in counterclockwise direction in the figures. In the arrangement shown the impression roller is mounted upon arms 18 pivotally mounted at their rear ends at 19 so as to enable the impression roller to move vertically with respect to the drum. The arms 18 at opposite sides of the machine are connected by a crossbar 20 which engages plungers 21 normally supported by coiled 35 springs 22 which bear at their lower ends upon a rigidly mounted crossbar 23. The arrangement is such that the impression roller 17 is normally pressed upwardly by the springs 22 into position for engagement with the face of the master sheet 15 on the drum section of greater diameter.

40 Suitable means of any approved type is provided for limiting the upward movement of the impression roller 17 for preventing engagement of the roller with the ink pad 14 carried by the drum section 13 of smaller size.

45 A short distance to the rear of the impression roller 17, a tray or table 24 of any suitable type is provided for supporting a pile of copy sheets 25 in engagement with a suitable flanged plate 26 which normally limits the forward movement 50 of the copy sheets. A forwarding roller 27 is

55

rotatably mounted in engagement with the top sheet 25 of the pile of copy sheets, being supported in position by means of a shaft 28. A mutilated roller 29 is rotatably mounted in position a short distance in front of the forwarding roller 27, being supported by means of a shaft 30. The arrangement is such that the rollers 27 and 29 cooperate with each other for forwarding the copy sheets 25 one at a time into position above the impression roller 17 as is clearly shown in Fig. 2. Inasmuch as the means for operating the rollers 27 and 29 and their cooperating parts form in and of themselves no part of the present invention, it is believed to be unnecessary to show or to describe the arrangement by which the operation of the rollers is effected.

This case is being filed as a division of my application Serial No. 266,518, filed April 7, 1939, Patent No. 2,260,330, October 28, 1941, covering improvements in duplicating apparatus. The details of the arrangement of the parts so far described are disclosed in said prior application to which reference may be made.

My improved stop means for limiting the forward movement of the copy sheets by engagement with the leading edges of the copy sheets as they are forwarded by the rollers 27 and 29 comprises two arms 31 at opposite sides of the machine, such arms in the arrangement shown being pivotally mounted on the hubs of the mounting arms 31a of the drum section 12. At their end portions, the arms 31 carry a crossbar 32 which in the arrangement shown is formed integrally with the adjacent portions of the arms 31, as is best shown in Fig. 4. As is disclosed in Fig. 1, the arms 31 are connected by means of coiled springs 33 with the end walls 34 of the drum section 13, such springs serving to hold the bar 32 normally in engagement with a radially positioned face portion 35 of the drum section 13. For cushioning the arms 31 with respect to engagement with the drum section 13, a bumper member 36, preferably of rubber, is provided on each of the arms 31.

Immediately below the drum, I have provided latch members 37 pivotally mounted by means of rivets 38 on brackets 39 at opposite sides of the machine. Each of the latch members 37 is provided with a spring 40 in connection therewith serving normally to hold the member swung to the limit of its movement in counterclockwise direction in said Fig. 1, the motion of the latch device in counterclockwise direction in said figure being limited by stop devices comprising bumpers 41, preferably of rubber. As is clearly shown in Fig. 1, the latch members 37 are provided at their upper ends with lugs 42 which normally extend into the paths of movement of rollers 43 carried by the crossbar 32, the rear faces of the lugs 42 being obliquely disposed, as is clearly shown in said Fig. 1.

In the rotation of the drum in counterclockwise direction in Fig. 3 by power applied through the driving shaft 11, the crossbar 32 stands normally in engagement with the face portions 35 of the drum section 13, in which position the crossbar travels about with the drum. When however the crossbar reaches the position as shown in Fig. 1, the rollers 43 are brought into engagement with the lugs 42 by which the forward movement of the crossbar 32 is stopped so as to permit the crossbar to remain stationary during the immediately following continued rotation of the drum, this being permitted by reason of the fact that the crossbar 32 is located

in the opening 16 in the face of the drum. When bumper plates 44 carried by the drum section 12 are brought into contact with the bumper members 36, so as to apply increased pressure for urging the crossbar 32 toward the right in Figs. 1 and 2, the rollers 43 by a camming action upon the obliquely disposed faces of the lugs 42 force the latch members 37 to swing in clockwise direction in said figures against the action of the springs 40 for freeing the crossbar 32 from such latch members. As soon as the rollers 43 clear the lugs 42, the springs 33 serve immediately to carry the crossbar 32 again to its normal position as shown in Fig. 3.

As is clearly shown in Fig. 4, the crossbar 32 is provided with a groove 45 in its rear edge face in position to receive the forward edge of a copy sheet 25 as such sheet is moved forwardly by the rollers 27 and 29 over the impression roller 17. The sheet 25 is permitted to move into position above the impression roller 17 by reason of the fact that the copy sheets are fed forwardly at the time when the opening 16 of the drum is positioned opposite to the impression roller 17, as shown in Fig. 1. The arrangement is such that the stop bar 32 is released from the latch means through the medium of the bumper plates 44 pressing on the bumpers 36 at just the moment when the drum section 12 comes into engagement with the top face of the impression roller 17. It is thus clear that when the copy sheet 25 is released by the stop bar 32, the sheet is immediately gripped by the section 12 of the drum and the impression roller 17 for continued movement forwardly with the drum.

In the construction as shown, means comprising a crossbar 46 carried by pivoted arms 47 is provided for stripping the front end of a copy sheet in due time from the drum section 12 for delivery along a supporting plate 48 and between rollers 49 and 50 into a tray 51. Since these parts form no part of the present invention and are shown complete in my said earlier application Serial No. 266,518, they are not further described herein.

While the form and arrangement as shown and described are preferred, the invention is not to be limited to such arrangement, except so far as the claims may be so limited, it being understood that changes might well be made in the construction without departing from the invention.

I claim:

1. In a duplicating machine, the combination of a frame, a drum rotatably mounted on said frame, means for driving said drum, a platen rotatably mounted on said frame in position to engage said drum so as to rotate at the same surface speed therewith, means for securing a form removably in position on said drum, stop means adapted normally to travel around with the drum a short distance in advance of said form and movable circumferentially of the drum toward said form against the action of a spring, means adapted upon each revolution of the drum to have releasable engagement with said stop means for holding the stop means stationary slightly in advance of said platen while the drum continues to rotate, means for feeding a copy sheet into engagement with said stop means so as to align said copy sheet into normal operative position above said platen, and means adapted when the form on the drum reaches approximately normal printing position with respect to the held copy sheet to release said stop means

from said holding means for freeing the copy sheet so as to be forwarded by the cooperative action of the drum and platen in printing relation to the form.

2. In a duplicating machine, the combination of a frame, a drum rotatably mounted on said frame, means for driving said drum, a platen rotatably mounted on said frame in position to engage said drum so as to rotate at the same surface speed therewith, means for securing a form removably in position on said drum, stop means adapted normally to travel around with the drum a short distance in advance of said form and movable circumferentially of the drum toward said form against the action of a spring, means adapted upon each revolution of the drum to have releasable engagement with said stop means for holding the stop means stationary slightly in advance of said platen while the drum continues to rotate, means for feeding a copy sheet into engagement with said stop means so as to align said copy sheet into normal operative position above said platen, and means carried around with the drum adapted by pressure forwardly on said stop means when the form reaches approximately normal printing position with respect to the held copy sheet to release the stop means for freeing the copy sheet so as to be forwarded by the cooperative action of the drum and platen in printing relation to the form.

3. In a duplicating machine, the combination of a frame, a drum rotatably mounted on said frame, means for driving said drum, a platen rotatably mounted on said frame in position to engage said drum so as to rotate at the same surface speed therewith, means for securing a form removably in position on said drum, stop means adapted normally to travel around with the drum a short distance in advance of said form and movable circumferentially of the drum toward said form against the action of a spring, latch means adapted upon each revolution of the drum to engage said stop means and to hold the stop means stationary slightly in advance of said platen while the drum continues to rotate so as to tension said spring as the drum continues to rotate and adapted upon the application of increased pressure thereon to release the stop means, means for feeding a copy sheet into engagement with said stop means so as to align said copy sheet in normal operative position above said platen, and means adapted when the form on the drum reaches approximately normal printing position with respect to the held copy sheet to apply pressure on said stop means for releasing it so as to free the copy sheet for forward movement by the cooperative action of the drum and platen in printing relation to the form.

4. In a duplicating machine, the combination of a frame, a drum rotatably mounted on said frame, means for driving said drum, a platen rotatably mounted on said frame in position to engage said drum so as to rotate at the same surface speed therewith, means for securing a form removably in position on said drum, stop means adapted normally to travel around with the drum a short distance in advance of said form and movable circumferentially of the drum toward said form against the action of a spring, latch means adapted upon each revolution of the drum to have releasable engagement with said stop means for holding the stop means stationary slightly in advance of said platen while the drum continues to rotate, means adapted to feed a

copy sheet forwardly into engagement with said stop means so as to bring said copy sheet into normal operative position above said platen, and means adapted by pressure forwardly on said stop means when the form on the drum reaches approximately normal printing position with respect to the copy sheet to release said stop means from said holding means for freeing the copy sheet for forward movement by the cooperative action of the drum and platen in printing relation to the form.

5. In a duplicating machine, the combination of a frame, a drum rotatably mounted on said frame, means for driving said drum, a platen rotatably mounted on said frame in position to engage said drum so as to rotate at the same surface speed therewith, means for securing a form removably in position on said drum, stop means adapted normally to travel around with the drum a short distance in advance of said form and movable circumferentially of the drum toward said form against the action of a spring, a plate pivotally mounted in position close to the path of movement of said stop means, a spring normally holding said plate yieldingly in position for engaging said stop means upon each revolution of the drum so as to hold the stop means stationary at a point slightly in advance of said platen during the continued forward rotation of the drum and adapted upon the subsequent application of heavy pressure to the stop means to yield for releasing said stop means, means adapted to feed a copy sheet forwardly into engagement with said stop means so as to align said copy sheet into normal operative position above said platen, and means adapted when the form on the drum reaches approximately normal printing position with respect to the copy sheet to apply pressure on said stop means for releasing it for freeing the copy sheet for forward movement by the cooperative action of the drum and platen in printing relation to the form.

6. In a duplicating machine, the combination of a frame, a drum rotatably mounted on said frame, means for rotating said drum, a platen rotatably mounted on said frame in position to engage said drum so as to rotate at the same surface speed therewith, means for securing a form removably in position on said drum, two arms pivotally mounted on an axis extending longitudinally of the drum, a stop member carried by said arms in advance of said form and movable toward and from the form, spring means normally holding said stop member at the limit of its movement away from the form, means adapted upon each revolution of the drum to releasably hold said stop member stationary a short distance in advance of said platen while the drum continues to rotate, means for feeding a copy sheet into engagement with said stop member so as to align said copy sheet into normal operative position above said platen, and means carried around with the drum adapted upon each revolution of the drum when the form on the drum reaches approximately normal printing position with respect to the copy sheet to apply pressure forwardly on said stop means for releasing said stop member from said holding means for freeing the copy sheet for forward movement by the cooperative action of the drum and platen in printing relation to the form.

7. In a duplicating machine, the combination of a frame, a drum rotatably mounted on said frame having its side wall cut away at one side portion, means for rotating said drum, a platen

rotatably mounted on said frame in position to engage said drum so as to rotate at the same surface speed therewith, means for securing a form removably in position on said drum with its leading edge positioned adjacent to the side opening in said drum, two arms pivotally mounted on an axis extending longitudinally of the drum, a stop member carried by said arms so as to be movable circumferentially of the drum in said side opening, spring means normally holding said stop member at the limit of its movement away from the form, pressure releasable latch means adapted upon each revolution of the drum to releasably hold said stop member stationary a short distance in advance of said platen while the drum continues to rotate, means for feeding a copy sheet into engagement with said stop member so as to align said copy sheet into normal operative position above said platen, and bumper means carried by said drum adapted upon each revolution of the drum when the form on the drum reaches approximately normal printing position with respect to the copy sheet to apply pressure forwardly on said arms for releasing said stop member from said holding means for freeing the copy sheet for forward movement by the cooperative action of the drum and platen in printing relation to the form.

8. In a duplicating machine, the combination of a drum rotatably mounted in position comprising two sections in spaced relation to each other circumferentially at one side at least of the drum, means for rotating said drum, means for securing a form removably in position on one of said drum sections with its leading edge positioned adjacent to the opening between the two sections, a platen rotatably mounted in position to engage said form so as to rotate at the same surface speed therewith, two arms pivotally mounted on an axis extending longitudinally of the drum, a stop member carried by said arms so as to be movable circumferentially of the drum in the open space between the sections adjacent to the leading edge of said form, spring means normally holding said stop member at the limit of its movement away from the form, pressure releasable latch means

adapted upon each revolution of the drum releasably to hold said stop member stationary a short distance in advance of said platen while the drum continues to rotate, means for feeding a copy sheet into engagement with said stop member so as to align said copy sheet into normal operative position above said platen, and bumper means carried by said drum adapted upon each revolution of the drum when the form on the drum reaches approximately normal printing position with respect to the copy sheet to engage cooperating bumper means on said arms for applying pressure forwardly on said stop means so as to release said stop member from said holding means for freeing the copy sheet for forward movement by the cooperative action of the drum and platen in printing relation to the form.

9. In a duplicating machine, the combination of a drum rotatably mounted in position and having an opening in its wall at one side portion, a platen rotatably mounted in position to engage said drum so as to rotate at the same surface speed therewith, means for securing a form removably in position on said drum with its leading edge adjacent to the rear edge of said opening, stop means adapted normally to travel around with the drum a short distance in advance of said form and movable circumferentially of the drum in said opening toward said form, yielding means normally holding said stop means moved forward in spaced relation to said form, means adapted upon each revolution of the drum releasably to engage said stop means for holding the stop means stationary immediately in advance of said platen while the drum continues to rotate so as to engage the leading edge of a copy sheet fed into said opening in the drum for stopping the copy sheet and aligning it into normal operative position above said platen, and means adapted when the form on the drum approaches normal printing position to force said stop means out of engagement with said holding means for freeing the copy sheet so as to permit the sheet to be forwarded by the cooperative action of the drum and platen in printing relation to the form.

MORRIS P. NEAL.
